STUFFED TOY ANIMAL FIGURE UNIT

Mary Caroline Nors, Santa Monica, Calif.

Application June 13, 1949, Serial No. 3,247

Term of patent 3½ years

(Cl. D34—2)

To all whom it may concern:

Be it known that I, Mary Caroline Nors, a citizen of the United States, residing at Santa Monica, in the county of Los Angeles and State of California, have invented a new, original, and ornamental Design for Stuffed Toy Animal Figure Unit, of which the following is a specification, reference being had to the accompanying drawing, forming a part thereof.

I claim:

The ornamental design for a stuffed toy animal figure unit, substantially as shown.

MARY CAROLINE NORS.
